UNITED STATES PATENT OFFICE

99,594

DESIGN FOR A SPACE HEATER

George L. Bridge, Clayton, Mo.

Application September 30, 1935, Serial No. 58,758

Term of patent 7 years

To all whom it may concern:

Be it known that I, George L. Bridge, a citizen of the United States, residing at Clayton, county of St. Louis, State of Missouri, have invented a new, original, and ornamental Design for a Space Heater, of which the following is a specification, reference being made to the accompanying drawing forming a part thereof.

The figure is a perspective view of a space heater, showing my design, the undisclosed side being like the side shown.

A notable feature of my invention resides in the provision of a metal case having embossed stripping on the front face thereof which defines a number of panels, the said embossed stripping being of a color contrasting with that of the panels.

I claim:

The ornamental design for a space heater as shown and described.
